UNITED STATES PATENT OFFICE.

ANDREW J. HEAVNER AND RICHARD THORNTON, OF PITTSFIELD, ILL.

WHEEL-CULTIVATOR.

SPECIFICATION forming part of Letters Patent No. 327,400, dated March 9, 1886.

Application filed July 20, 1885. Serial No. 172,099. (No model.)

To all whom it may concern:

Be it known that we, ANDREW J. HEAVNER and RICHARD THORNTON, citizens of the United States of America, residing at Pitts- 5 field, in the county of Pike, in the State of Illinois, have invented a new and useful Culti- vator, of which the following is a specification.

Our invention relates to improvements in 10 cultivators of that class specially known as "wheel-cultivators;" and the object is to sim- plify and improve existing implements of that character.

We attain the purpose of our improvements by means of the mechanism illustrated in the 15 accompanying drawings, forming a part of this specification, and in which Figure 1 is a perspective view of our improved implement. Fig. 2 is a central longitudinal sectional view. Fig. 3 is a plan view thereof. Fig. 4 is a de- 20 tail view of the sleeve and shifting devices. Fig. 5 is a detail view of the plow-standard and mode of attaching it, and Fig. 6 is a central sectional view taken through the line $x-x$ of Fig. 5.

25 Similar parts are identified by similar letters of reference in the different views.

The letter A designates the wheels supporting the axle B, the latter being formed with a bail, b, carrying the carriage or frame C. 30 This frame C is comprised of substantial side bars, c, connected by end bars, c', and intermediate cross-bar, c".

The letter D designates the seat, the stem or 35 foot d thereof being secured to the board d', resting on the cross-bars d", secured to the rear cross-bar, c', and bar d", the latter being secured to the side bars of the frame. About the standard of the seat, or about a standard projected from and secured to the board sus- 40 taining the seat, is secured a spring, d", which may consist of a spring-rod wrapped about such standard, with its arms d" extending forward from the seat, and arranged to have a spreading force, in order that when the free 45 ends of the spring are set against the inner edges of the levers connected to the forward shovels the spring shall operate to press apart the levers when drawn together by the pressure from an opposite direction.

50 The letter E designates levers having their forward ends pivotally attached to the cross- bar c" of the frame, and their free ends extend-

ing back over the axle, and arranged with their inner edges resting against the arms of the spring secured to the foot or standard of 55 the seat, substantially as shown in Fig. 3 of the drawings. These levers have formed in them slots e, longitudinally arranged therein, and adapted to receive the projected or ex- tended end of the standards of the forward 60 shovels, so that the direction of the shovels may be guided by operation of the levers at the will of the driver.

The letter F designates the tongue, pivoted or otherwise suitably secured to the cross-bar 65 c" at f, and also secured against side displace- ment by a strap fitted to the tongue and se- cured to the front cross-bar of the frame, as seen at f'.

The letter G represents the plow-beams. 70 These are provided with vertical standards g, secured to the rear ends thereof, the upper end of which standards is passed through an adjustable sleeve, g', secured to the end cross- 75 bar of the frame, as hereinafter stated. These sleeves g' are formed or provided with a bolt, g", projected from their rear wall, and termi- nating in a head, g", formed with a hole, g", intended as a bearing for the lever-bar, which is projected through these holes of the bolt- 80 heads, as hereinafter stated. The neck of these bolts g" is screw-threaded, and a threaded nut, g", fitted thereto, whereby the sleeve may be secured in position as may be desired. Se- 85 cured to the side of the sleeve is a small sheave or sprocket-wheel, g". Through the holes in the heads of the bolts of the sleeves is fitted a lever-bar, g", having a lever-handle, g", secured to one end, and arranged to be conveniently accessible to the driver; and at each end of the 90 lever-bar g" is fitted a grooved or sprocket sector, g", to the inner or upper end of which is fastened a line or chain which passes down over the sector; thence over the sheave or sprocket at the side of the sleeve, and, extend- 95 ing down, has its lower end secured to the plow-beam, substantially as shown in the drawings. The rear cross-piece of the frame is formed with longitudinal slots g", extended through the cross-piece from rear to front, 100 and in these slots the sleeves are secured by means of their bolts and nuts, the purpose being to permit the sleeves to play for the length of the slots; or they may be set therein

at any position desired by simply clamping them in position. By the same means the beams of the plow can be arranged at the required distance apart. By means of this mechanism the rear ends of the plow-beam can be raised and the plow lifted from the ground, or their depth regulated thereby. Simply moving the lever in the right direction effects the purpose.

10 The letter H designates brackets secured to the front cross-piece of the frame, and comprised of the depending bars *h*, which are perforated, substantially as shown, to receive the shaft or pintle of a sheave, *h'*, and connected at their lower ends by means of a cross-bar, *h''*. Attached to a suitable point in the side bar of the frame are braces *h³*, extending from their point of attachment to the frame to the lower part of the outside bar of the bracket, the object being to strengthen the devices or brackets. To the forward end of each beam is secured a sleeve, *h⁴*, which is passed over the cross-bar of the bracket, and, being provided with a set-screw, may be set 15 in any desired position on the cross-bar, thus affording a lateral adjustment to the beam to suit different widths of growth.

The letter I designates the front shovels or plows, the lower part or shovel, *i*, being made 20 of any of the approved forms, and having attached thereto a standard composed of two sections—a lower one, *i'*, and an upper one, *i''*—arranged with their side faces in contact, and fastened together by means of an iron pin 25 or bolt, *i³*, passed through the spliced parts above the bracket, substantially as seen. The standard in immediate connection with the plow is slotted, as at *i⁴*, and has fitted in said slot a flat bolt, *i⁵*, formed with a side projecting lug or finger, *i⁶*, adapted to set with its rear face against the face of the upper splice of the standard and serve as a brace-piece. This flat bolt is provided with a hole through each end. Through the rear hole, *i⁷*, is projected a wooden 30 pin, *i⁸*, which rests against the face of both sections of the standard and serves as a break-pin in cases wherein the strain upon the standard is more than it should withstand, the pin giving away under such exigencies, and thus 35 saving the integrity of the standards and the plow. To the front end of the bolt *i⁵* is fastened the brace-chain *i⁹*, having its other end linked to the end of the bracket or rod *i¹⁰*, secured to the beam of the plow, the object being to secure the parts together strong enough 40 to withstand any ordinary strain, and yet so that they shall, in case of accident or undue strain, be torn asunder without material damage to either section. The upper section of 45 the standard of the forward plow is projected through the slots *e* of the levers *E*, in order that the course of the shovel may be guided and controlled by the operation of the lever.

The letter J designates brackets adapted to 50 hold the standards of the plow or shovel. These brackets consist of a substantial metal bar formed with a cross-head, *j*, perforated to

receive a bolt, and the arms or side pieces, *j'*, provided with perforations in their free end *j''*. A bolt, *j³*, is passed through the perforation of 70 the cross-head and through the beam, and secured by means of a nut on its projecting end. This connection, it will be seen, permits the bracket to be turned and set so as to receive the standards of the shovel at any desired inclination. A bolt, *j⁴*, is projected through the end perforation of the bracket and through the standard of the shovel, and secured by any suitable means. This latter connection, it will be seen, permits the standard of the plow to 80 be swung in either direction about the bolt, holding it in the bracket, and the result of the connections is, that the plow can be turned to any position of incline on the axial bolt of the bracket, and at the same time may be moved 85 sidewise by turning on the axial bolt of the standards.

The letter K represents the hind shovels, having their standards secured in the brackets *J* identical with the forward shovels, except that the standards of these rear shovels are not extended above the brackets, except sufficiently to give secure fastenings. A brace, *k*, extends from the standard of the shovel to the beam, and the incline of the shovel is set 95 by means of perforations in the brace in its free end, and securing it to a pin on the beam, substantially as seen in the drawings.

The letter L designates the double-tree, pivotally secured to the center of the bail of the 100 axle, as at *l*. To each end of the double-tree is attached a rod, *l'*, which extends therefrom to the forward part of the carriage, being passed through the sheaves of the brackets, and has connected therewith the single-tree *l''*.

The operation is readily gleaned from the foregoing description of the parts and their functions, but may be here stated as follows: The draft may be regulated by means of shifting the sheaves on the brackets at the front of 110 the beam to a higher or lower position, whereby the line of draft is set accordingly. The depth of the shovels is regulated by means of the lever at the hind end of the frame and beam, and the beams may be set to any width by lateral movement on the front rods of the brackets, and by movement of the sleeves in the slots at the rear piece of the frame. The front shovels are arranged to operate independently of 115 the back shovels in this, that they may be 120 lined by means of the levers extending within reach of the operator.

The general construction of the implement or machine admits it to be made in a compact form, whereby the draft may be lightened, and the 125 weight brought more directly upon the axle. Access to the lever is convenient, and the driver has free and full view of the forward shovels, and, by means of the lever hinged to the frame and controlling the projected standards of the 130 front shovels, may guide them as desired.

What we claim as our invention, and desire to secure by Letters Patent, is—

1. In combination, the frame *C*, provided

with depending brackets H at its front end and a slotted cross-piece at its rear end, the beams G , carrying the plows, and provided with sleeve h , fitted to their front end, adjustable laterally on the cross-bar of the bracket, and provided with standards g at their rear end, the sleeves g' , adjustably secured within the slots of the rear cross-piece of the frame, a bar, g' , mounted on journals in the projecting ends of the bolts of 10 the adjustable sleeves and provided with a lever-handle, and a chain connecting the lever and the plow-beam, substantially as described, and for the purpose stated.

2. In combination with the front shovel standards secured to the plow-beams and the levers hinged to the top of the frame and formed with slots to receive the projecting upper parts of the plow-standards, the spring secured between the free ends of said levers, with 15 its free ends bearing against the levers, substantially as described, and for the purpose stated.

3. In combination, the seat mounted on the frame of the carriage, the spring secured about the foot of the seat, with its free ends bearing 20 apart, and the levers having one end pivoted to the frame and the other end bearing against the arm of the spring, and having the standards of the forward plows adjustably connected therewith, substantially as described, and for 25 the purpose stated.

4. The plow-standard consisting of two sections joined together by a metal retaining-bolt at the upper end of the splice, and by a bolt formed with a side projecting lug to fit against 30 the front of the spliced section and pass through a slot in the plow-standard, and secured by a

break-pin passed through its projecting end across the rear faces of the splice, substantially as described.

5. The combination of the frame having slots 40 in its rear cross-piece and the plow-beams provided with standards on their rear ends with the adjustable sleeves, provided with threaded bolts and nuts disposed in the slots of the rear cross-piece of the frame, substantially as described, and for the purpose set forth. 45

6. In combination, the frame having a slotted rear cross-piece, the plow-beams provided with standards on their rear end, laterally-adjustable sleeves having sheaves or sprocket-wheels journaled thereto and provided with bolts disposed in said slots of the frame, the lever-bar mounted in the heads formed on the ends of the sleeve-bolts and provided with sectors, and chains passed over the sectors and 50 the sheaves on the sleeves and fixed to the lever and plow-beam, substantially as described, and for the purpose set forth. 55

7. The sleeve having a sheave pivotally attached thereto and formed with a threaded projecting bolt provided with a threaded nut, said bolt terminating in a fixed head with a hole set at right angles to the passage in the sleeve, substantially as described.

In testimony whereof we have hereunto subscribed our names in the presence of two attesting witnesses.

ANDREW J. HEAVNER.
RICHARD THORNTON.
